UNITED STATES PATENT OFFICE.

ROBERT T. JOHNSTON, OF SCOTCH PLAINS, NEW JERSEY, ASSIGNOR TO WOOD & NATHAN COMPANY, OF NEW YORK, N. Y., A CORPORATION OF NEW YORK.

PLATE-BENDING MACHINE.

1,116,436.

Specification of Letters Patent.

Patented Nov. 10, 1914.

Application filed April 6, 1907, Serial No. 366,769. Renewed April 8, 1914. Serial No. 830,539.

To all whom it may concern:

Be it known that I, ROBERT T. JOHNSTON, a citizen of the United States, residing at Scotch Plains, in the county of Union and 5 State of New Jersey, have invented a new and useful Plate-Bending Machine, of which the following is a specification.

This invention relates to a machine which while capable of general use for bending 10 purposes is especially adapted for bending printing plates, such as those used in intaglio printing.

The principal objects of the invention are to provide means whereby plates of such a 15 character may be bent to shape with accuracy in a simple and convenient manner in such a way that their surfaces will not be marred, to provide means preferably arranged inside the periphery of the plate carrying cylinder for forming a clamping lip on the plate by means of which it may be attached to the printing cylinder, and to accomplish these results in a simple manner by means of a machine which will be inexpensive in cost of construction, and will 25 have few parts which are liable to get out of order in use.

Further objects and advantages of the invention will appear hereinafter.

30 Reference is to be had to the accompanying drawings which illustrate one embodiment of this invention and in which—

Figure 1 is an end elevation of one form of a bending machine. Fig. 2 is a side elevation of the same partly broken away to 35 show the interior construction. Fig. 3 is a central transverse sectional view of Fig. 2. Fig. 4 is a fragmentary end elevation with portions removed. Fig. 5 is a fragmentary sectional view of the rotary carrier showing the clamping and lip forming device. Fig. 6 is an end elevation of a portion of one of the sprocket wheels with 40 the chain thereon, and Fig. 7 is a fragmentary plan of the endless series of rollers.

The machine is shown as provided with a 45 movable carrier 10 which preferably rotates, upon which the plates *p* which is designed to be bent is secured. In order to clamp the plate to the carrier, the latter is provided with a clamping block 11 having a jaw 12 with a surface inclined with respect to the

surface of the carrier. The carrier is provided with a corresponding jaw 13, and between these jaws the end of the plate is secured by tightening up the block 11 by means of a screw 14 or the like. The carrier is designed to act to bend the plate by rotating and drawing it into a space formed 55 between the carrier and the inner surface of the concave bending shell 15 which is made cylindrical and concentric with the rotary carrier. The mere drawing of the plate into the space between the shell and carrier 60 by the rotation of the latter would result in bending the plate, and this may be done in some cases, it being understood that a sheet of hard paper or other suitable material is mounted on the carrier with the plate 65 to protect its face. As the plate is bent to the circumference of the cylinder, its end which is clamped between the jaws 12 and 13 is bent over to form the clamping lip by means of which the plate is to be mounted 70 on the cylinder of the printing press. In order that the plate may be more accurately bent to shape, and to accomplish that without any unnecessary friction on the surface of the plate or the paper which is applied 75 to it, I have provided the device with an endless traveling concave bending surface comprising a series of traveling rollers 16, each one free to rotate on its axis. In order to carry these rollers each one is 80 provided with a cavity in its end, and a pair of endless chains 17 are mounted in such position that studs 18 projecting therefrom into these cavities hold the rollers in position upon the chain, each one 85 being free to rotate on its own axis. The chain and rollers preferably pass around the shell or segment 15, as is most clearly indicated in Fig. 3. The chains pass over sprocket-wheels 19 loosely mounted on 90 a shaft 20. The concave shell 15 is provided with convex semi-cylindrical ends 21 over which the rollers can travel in an obvious manner, to bend the lip on the plate. The rollers are supported by one of these convex 95 surfaces at this time. They are driven by frictional contact with the plate or protecting material thereon, which gives a perfect rolling action between the plate and rollers and eliminates all chances of rubbing 100 or marring the surfaces of the plates. The

sprockets 29 on the opposite shaft 30 are fastened to it and tend to keep the rollers parallel to the plate carrying cylinder.

The shaft 20 may be provided with any desired kind of power mechanism, but the machine can most conveniently be operated by hand, and I have shown a crank-handle 22 for turning the shaft which is provided with a pinion 23 meshing with an internal gear 24 on a shaft 25, on which the rotary carrier 10 is mounted.

It will be seen that by means of this construction the operator can stand in such position as to face the machine while turning the crank in the natural way to the right. The bending rollers which constitute the surface against which the plate bears are supported through their length by the concave surface of the bending shell, and consequently they present substantially the same shape to the plate to be operated upon, moreover, as the plate enters the space between the two bending surfaces it first engages the convex surface formed by the rollers on the end 21, so that the plate is gradually brought to its curved shape.

While I have illustrated and described a particular form in which I prefer to embody this invention, I am aware that many modifications may be made therein without departing from the scope of the invention as expressed in the claims. Therefore, I do not wish to be limited to the particular construction shown, but

35 What I do claim is:—

1. A plate bending machine having a rotary cylindrical plate carrier for receiving the plate, and a frame provided with a substantially radial surface for engaging the extreme edge of the plate and a second surface between the first named surface and the circumference of the plate carrier forming an angle therewith, whereby the plate is bent within the circumference of the carrier to 45 form a lip.

2. In a plate bending machine, the combination of a rotary cylindrical plate carrier for receiving the plate and having a recess therein, of a clamp fitting in said recess for 50 clamping the edge of the plate therein, said clamp having a substantially radial surface for engaging the extreme edge of the plate, and a second surface between the first named surface and the circumference of the plate 55 forming an angle therewith, whereby the plate is bent within the circumference of the carrier to form a lip, and means outside the carrier for bending the plate around the same.

60 3. A bending machine comprising a stationary concave bending shell having an endless traveling surface and a traveling convex surface adjacent thereto.

4. In a bending machine, the combination of a concave shell, and a movable carrier arranged adjacent thereto, said shell having an endless concave bending surface movable along the concave part of the shell. 65

5. In a plate bending machine, the combination of a rotary carrier, and a shell arranged adjacent thereto having a concave surface for receiving the carrier and a convex surface at its end, and an endless series of rollers adapted to pass over the convex surface to bend a plate held by the carrier. 70

6. In a plate bending machine, the combination of a rotary plate carrier, a shell having a concave surface for receiving the carrier and a convex surface at the end thereof, and an endless series of rollers 80 adapted to move in contact with said surfaces and supported by the convex surface when a plate on the carrier comes into contact with the rolls for receiving its initial bend. 75

7. In a bending machine, the combination of a concave shell, a rotary carrier, a pair of endless chains arranged adjacent to the shell, and a series of freely rotatable rollers on said chains movable along the concave 85 surface of the shell adjacent to the rotary carrier.

8. In a plate bending machine, the combination of a concave shell, a carrier for the plates, a pair of endless chains, sprocket-wheels for supporting said chains, each chain having a series of studs extending toward the other chain, and a series of rollers mounted to freely rotate on said studs. 95

9. In a plate bending machine, the combination of a concave shell, a carrier, an endless series of rollers arranged on the surface of the shell between the shell and the carrier, and means for moving the carrier and rollers. 100

10. In a plate bending machine, the combination of a rotary carrier, a shell having a surface adjacent to the carrier, a series of rotatable rollers, chains for supporting said rollers, sprocket wheels carrying said chains, 110 a shaft on which said sprocket wheels are loosely mounted, and means connected with said shaft for rotating the rotary carrier.

11. In a plate bending machine, the combination of a rotary carrier, a shell having a surface adjacent to the carrier, a series of rotatable rollers, chains for supporting said rollers, sprocket wheels carrying said chains, 115 a shaft on which said sprocket wheels are loosely mounted, a pinion on the shaft, an internal gear connected with the rotary carrier and meshing with the pinion, and a crank on the shaft for operating the same. 120

12. In a plate bending machine, the combination of a plate carrier, a shell adjacent 125 thereto, an endless series of rolls adapted to

pass between the carrier and shell, a pair of shafts, one of which is positively driven, sprocket wheels loosely mounted on said driven shaft for carrying said rolls, and 5 sprocket wheels fixed to the other shaft for guiding the rolls and keeping them in alinement with the plate carrier.

In testimony whereof I have hereunto set my hand, in the presence of two subscribing witnesses.
